ATTORNEYS

UNITED STATES PATENT OFFICE.

BENTLEY R. HOOKS, OF AMARILLO, TEXAS.

SAFETY APPLIANCE FOR RAILWAY SWITCHES.

Application filed November 14, 1922. Serial No. 600,868.

To all whom it may concern:

Be it known that I, BENTLEY R. Hooks, a citizen of the United States, and a resident of Amarillo, in the county of Potter and State of Texas, have invented certain new and useful Improvements in Safety Appliances for Railway Switches, of which the following is a specification.

This invention relates to switches and is more particularly directed to a device for preventing the so-called "split switch wrecks."

Heretofore it has been proposed to construct devices for preventing the switch points of a railroad switch from forming a gap with the main rails whereby the usual flange of the wheels of a train will cut through the gap and cause a train going at a great speed to be thrown into a switch and de-railed.

An object of this invention is the provision of a device which does not prevent gaps being formed but which is adapted primarily for guiding the wheels of a train past a defective switch and maintaining said train on its direct route of travel.

A further object of the invention is the provision of a safety device for laterally shifting the wheels of a train from a defective switch point and which is also adapted to prevent injury to the switch points.

Other objects and advantages of the invention will become apparent during the course of the following description.

The invention is illustrated by way of example in the accompanying drawings, in which,

Figure 1 is a plan view of a switch showing my safety device in position relative to the switch points.

Figure 2 is a side view of my safety device applied to a rail.

Figure 3 is a view in perspective of the safety device constructed according to my invention.

Figure 4 is a transverse vertical section of the same.

Figure 5 is a transverse vertical section of the safety device showing a modified form of means for clamping the safety device to a rail.

Referring to the drawings, 1 and 2 designate a pair of the main rails, which in cooperation with the switch point 3 of the switch rail 1^a, are adapted to maintain a train moving over the rails on its direct

route of travel. The switch point 4 is adapted to be moved with the switch point 3 in the direction indicated by the arrow in Figure 1 to form a gap between the switch point 4 and the main rail 2 for permitting the train to continue its travel along the rails 1 and 2 in a direct line. When the switch points 3 and 4 are moved in a direction which is opposite to the direction indicated by the arrow, the train will be shifted to the rails 5 and 6 which are curved away from the main rails 1 and 2.

Means for moving the switch points 3 and 4 is not shown since it is an old and well known feature in the art.

Due to a defective switch or to defective switch points the switch point 3 frequently forms a gap with the main rail 1 and through which the flanges of a wheel will pass, shifting the train to the tracks 5 and 6. When the train is travelling at a high speed such sudden shifting of the train will cause de-railment of the same. In order to prevent the flanges of the wheels of a train from passing through the gap of such a defective switch, I have deformed the main track rail 1 just in front of the point of junction of the switch rail and the main rail, which provides a deformation on the side of the main rail to engage the flange of the wheels of the train on that side and bodily shift the wheels outwardly from the main rail and sufficiently to guide the flange of the wheels away from the defective switch point and cause the wheels to continue travel along the main line represented by the tracks 1^a and 2.

This deformation may be formed by welding on the ball of the rail a cam-shaped member. The welding may be done by the oxy-acetylene process. Instead of welding the cam shaped member to the ball of a rail whereby the same forms an integral construction the cam-shaped member may be so constructed that it may be clamped to the rail as will be presently described.

Referring to the safety device which is designated by the numeral 7 and which is more particularly shown in Figures 2, 3 and 4, a main plate 8 is provided which is adapted to be located in face to face engagement with the web 9 of the rail and having a shoulder 10 at its upper end in engagement with the under side of the head flange 11 of the rail and with the other end of the plate having a shoulder 12 in engagement

with the lower face of the base flange 13. The plate is abruptly reduced toward its lower end and terminates in a shoulder 12. Offset from the plane of the plate 8 is an elongated upstanding cam member 14 which extends longitudinally of the plate and is provided with a lateral projection 15 which is tapered toward its opposite end and terminates at the ends of the plate 8. A rib 16 is formed below and cooperates with the shoulder 10 to connect the cam member 14 to the plate 8. Said rib likewise provides means for strengthening the plate at this point.

15 The plate is provided with a pair of perforations adapted to receive bolts 17, the heads 18 of which have a portion cut away to form a lug 19 which is adapted to be received within a notch 20 formed in the rib 16 whereby rotation of the bolts 17 is prevented. A lock washer 21 mounted on the opposite edge of the bolt 17 which projects beyond the other face of the web 9 is engaged between the web and a nut 22 having a threaded engagement with the threaded end of the bolt 17.

Reinforcing members 23 are formed on the plate 8 adjacent the perforation in the plate through which the bolts 17 pass for strengthening the plate at these points.

As shown in Figure 4, the inner face of the plate 8 adjacent the shoulder 10 is cut away as shown at 24 providing a space between the plate and the rail at this point.

35 As shown in Figure 5, a modified form of securing means is employed for locking the safety device to a rail. The safety device 7^a is similar in all respects to the safety device 7 of Figures 1 to 4 inclusive, but instead of perforating the said device I have provided a pair of clamping members 25 and 26 which are adapted to engage opposite sides of the foot flange 13 and are locked together by means of bolts 27 passing through the clamping member. No cut-away portion 24 is shown in the safety device 7^a but the shoulder 10^a snugly fits the rail between the web 9 and the under face of the head flange 11.

50 The clamp 26 is provided with a rib 28 which is seated between the shoulders 29 and 30 of the safety device 7^a with the bottom of the clamp being provided with a longitudinal groove 31 which is adapted to receive one longitudinal edge of the base flange 13.

The other member 25 of the clamp comprises a longitudinal bar having a longitudinal groove 32 of a shape to receive and snugly fit the opposite edge of the base flange 13 of the rail. The bolts 17 pass through aligned perforations in the members 25 and 26 and engage the bottom face of the base flange 13 and are provided with nuts for drawing up the clamping members for

maintaining the safety device 7^a wedged between one side of the rail and the member 26.

The clamping member 15 forms a projection or a deformation on the side of the main rail to be engaged by the flanges of the wheels of a moving train whereby the wheels are shifted laterally away from the rail to which the safety device has been applied so that the wheels will effectually engage the outer side of the switch point regardless of the fact that a gap has occurred between the switch point and a rail which is turned away from the main track. The cam, by laterally shifting the wheel away from the defective switch point, will cause the wheels to continue along their direct line of travel on the main route with the wheels on one side hugging the inside of the switch point instead of the wheel passing between the switch point and the offset rail.

Furthermore, the safety device by constantly shifting the wheels away from the switch point will prevent wear and tear upon the switch points which is a constant source of worry to railroad officials. It must be borne in mind that the action of the safety device is not to provide a cure for a defective switch point or to prevent the switch points from forming a gap, but it is primarily designed to deform the main rail in such a manner that the wheels of a swiftly moving train are shifted laterally to an extent whereby the wheels will pass beyond the switch point and over the main line of travel.

What I claim is:

1. A device of the character described comprising a plate adapted to be clamped to the web of a rail in front of the switch point of a switch, and having a cam member extending longitudinally of the plate with the cam member gradually increasing in thickness from its opposite ends toward its middle portion to form a lateral projection for causing a lateral shifting of the wheels of a train away from the switch point of a switch which is adapted to lie in contiguous relation with the rail.

2. A device of the class described comprising a plate adapted to be clamped to the web of a rail in front of the switch point of a switch, and having an offset portion extending upwardly in embracing relation with a side of the head flange of a rail, said offset portion forming a lateral projection extending outwardly from the plate, said lateral projection tapering in opposite direction from the center of the offset portion toward the ends thereof for causing a lateral shifting of the wheels of a train away from the switch point.

3. A device of the class described comprising a plate adapted to be clamped to the

web of a rail in front of the switch point of a switch, and having a shoulder adapted to engage the under side of the head flange of a rail, an upstanding flange offset from the 5 plate and connected to the plate by the shoulders, said upstanding flange being provided with a cam member adapted to engage the wheels of a train for causing a lateral shifting of the wheels away from the switch 10 point.

4. A device for preventing split switch wrecks at defective switches comprising a plate adapted to be clamped to the web of a rail in front of the switch point of a switch 15 and having a cam-shaped member for engaging the wheels of the train for causing said wheels to continue in a straight line along the main track thereby preventing the wheels from engaging the split switch and 20 forcing the wheels into the switch.

5. A device of the class described com-

prising a plate adapted to be clamped to the web of a rail in front of the switch point of a switch, said plate having spaced parallel longitudinally disposed shoulders engaging 25 the head flange and foot flange of a rail with the inner face of the plate in face to face engagement with the web of the rail, a longitudinal rib projecting outwardly from the shoulder on the plate which is located adjacent the head flange of the rail, an upstanding flange connected to the plate by the rib and last mentioned shoulder, said upstanding flange being provided with a lateral projecting cam member having its greatest 35 width at its middle portion and tapering outwardly toward its opposite ends, said plate being provided with spaced perforations, and means passing through the perforations for securing the plate to the rail. 40
